UNITED STATES PATENT OFFICE

JOSEPH ERLE DRUCKENMILLER, OF EDGE HILL, PENNSYLVANIA

BATHROOM FIXTURE

Application filed July 22, 1931. Serial No. 552,488.

My invention is a combined fixture for bathrooms, by which there may be provided at low cost a maximum of services within a minimum floor space, and which in addition to its utilitarian functions will provide a structure of well balanced and ornamental appearance permitting separate production of a tub section, lavatory section and storage compartment section, and their assembly in 10 a composite structure.

In accordance with my invention, there is provided a tub member having at one end thereof a foot extension having end and side walls projecting above the top of the 15 walls of the body portion of the tub. A lavatory member comprising a basin with end extensions or shelves is provided with an apron concealing the joints at the ends thereof between the lavatory member and the 20 upwardly projecting tub walls and between the lavatory member and a cabinet spaced from the tub. The lavatory extensions form top covers or closures for the foot 25 extension of the tub and for the compartment within the cabinet, which is suitable for use as a closet or drawer space. The lavatory member is substantially less in width than the body portion of the tub, the front 30 walls of the latter taper inwardly at each end thereof toward the front line of the lavatory and the body of the tub forms a spacious and readily enclosed "pan" for a shower.

The characteristic features and advantages of my improvements will further appear from the following description and the 35 accompanying drawing of an illustrative embodiment of my invention.

In the drawing, Fig. 1 shows a front elevation of my improved fixture installed; and 40 Fig. 2 shows a top plan view thereof.

As illustrated in the drawing, a tub member A has a body portion 1 and the foot extension 2 and has its front wall 3 bent inwardly, as at 4 and 5. A portion 5a of the 45 wall 5 and the end wall 6 of the foot extension project upwardly a substantial distance above the top of the wall sections 3, 4 and 5. The wall of the tub section may be of solid 50 porcelain but is preferably made of a double shell of enameled iron.

The lavatory member B contains a recess 7 forming a basin or sink and has the end extensions 8 and 9 forming shelves 10 and 11 on either side of the basin. The end extension 8 projects over the foot extension 2 55 above the projecting walls 5a and 6. The end extension 9 projects over a pedestal which is preferably in the form of a cabinet 12 spaced from the end wall 6 and containing a chamber 13 forming a drawer space or closet, 60 suitably closed by a hinged door 14. The lavatory section has a lip or apron 15 overlapping and concealing the joints between the lavatory member and the tub and cabinet respectively. 65

As will be observed, the positioning of the end section 8 over the foot extension 2 of the tub not only minimizes the space required for the fixture but gives a finished appearance to the tub and balances the proportions thereof, giving a substantially balanced effect to the angular wall 4 and the uncovered section of the wall 5 and a symmetrical appearing hexagonal outline for the body of 70 the tub. The body of the tub forms a suitable "pan" for a shower, which may be conveniently enclosed by providing a glass or other partition 16 above the end extension 8. The recess formed by the foot extension and 75 projecting walls and cover thereof receives and confines the splash from jets projected from the shower head 17, and if desired, glass leaves or a curtain (not shown) may be provided to enclose the space above the wall 80 sections 3, 4 and 5. 85

It will be noted that the foot extension 2 of the tub, together with the upwardly projecting walls 5a and 6, forms a pedestal for one end of the lavatory, and that said projecting walls substantially close the space between the foot extension and the lavatory and provide a splash guard therebetween. By having the 90 pedestals for the opposite ends of the lavatory spaced apart, an open space may be provided beneath the basin, for the feet or legs of a person using the same, thereby adapting the device to be also used as a dressing table 95 if desired.

Having described my invention, I claim:

1. A bathroom fixture comprising a tub 100

member having a body portion and a foot extension provided with upwardly projecting walls, a pedestal spaced from said foot extension, and a lavatory member having end shelves projecting over and supported upon said foot extension and said pedestal.

2. A bathroom fixture comprising a tub member having a foot extension with upwardly projecting side and end walls, a cabinet spaced from said foot extension and containing a compartment, and a lavatory member having end shelves projecting over and supported upon said foot extension and said cabinet.

15 3. A bathroom fixture comprising a bath tub body, a lavatory adjacent said body and having a basin and shelves at opposite ends of the basin, and pedestals beneath the shelves and spaced apart to provide an open space beneath the basin, one of said pedestals being hollow and containing a foot extension of said body.

25 4. A bath room fixture comprising a bath tub body, a lavatory adjacent said body, and two pedestals for said lavatory spaced apart to provide an open space therebetween, one of said pedestals being integral with said body and forming a foot extension therefor.

30 5. A bath room fixture comprising a bath tub body of substantially equal width and length and forming a "shower pan", a lavatory of less width than said tub body and extending longitudinally beyond one end of the same, and a hollow pedestal for said lavatory disposed at one end of said tub body and containing a foot extension therefor of less width than said body.

40 6. A bath room fixture comprising a bath tub body of substantially equal width and length and forming a "shower pan", a lavatory adjacent said body and of less width than the same, said lavatory having a bowl and shelves at opposite ends of the bowl, and pedestals beneath said shelves and spaced apart 45 to provide an open space therebetween, one of said pedestals being hollow and containing a foot extension for and of less width than said body.

50 7. A bath room fixture comprising a combined bath tub and "shower pan" having a body portion with a foot extension, a lavatory having a basin extending beyond said foot extension and an end shelf overhanging such foot extension and spaced above the same, and a wall extending between said foot extension and said shelf, and providing a splash guard therebetween.

60 8. A bath room fixture comprising a combined bath tub and "shower pan" having a body portion and a foot extension of less width than said body portion, extending longitudinally from one end thereof, a lavatory adjacent to and of less width than the body portion and disposed at a height above 65 the top of the body portion, said lavatory hav-

ing a basin disposed beyond said foot extension, and a shelf at one end of the basin, overhanging said foot extension, and one or more substantially vertical walls disposed between the top of the foot extension and the shelf and substantially closing the space therebetween.

In testimony whereof I have hereunto set my hand this 20th day of July, 1931.

J. E. DRUCKENMILLER.
